UNITED STATES PATENT OFFICE

RALPH C. MACUMBER, OF PORTLAND, MAINE

INTERNAL-COMBUSTION ENGINE

Application filed May 31, 1928. Serial No. 281,979.

This invention relates to internal combustion engines.

In the designing and manufacturing of two-stroke cycle engines, it has been found difficult to admit the explosive mixture into a cylinder at some time other than that at which the previously fired charge is exhausted from the cylinder, the result being that some of the fresh charge is exhausted with the fired charge. It also has been found difficult to properly effect compression of the incoming charge so as to derive the greatest efficiency from the explosion of the charges. In the manufacture of internal combustion engines in general, it has been the common practice to provide valve means for controlling the passage of fresh charges into and exhaust charges from the cylinder, such valve means usually requiring the use of cam shafts, chains, push rods, etc. It also has been the common practice to compress a given charge of the explosive mixture once previous to firing the charge, the compression of the charge taking place upon upward movement of the piston of a working cylinder.

An important object of the present invention is to provide a novel internal combustion engine of the two-stroke cycle type wherein many of the disadvantages of prior types have been eliminated, thus increasing the efficiency of the motor.

A further object is to provide an internal combustion engine wherein an extremely high compression ratio is obtained by means of novel compressing means associated with the working cylinders.

A further object is to provide a valveless engine of the two-stroke cycle type wherein a high compression ratio is obtained and wherein the explosive charges are admitted into the working cylinders after the completion of the previously fired charges.

A further object is to provide a motor of the character referred to wherein alternate cylinders and pistons are provided for compressing and firing the charges, the cylinders and pistons being substantial duplicates of each other.

A further object is to provide an internal

combustion engine of the character referred to wherein the desired results are obtained without the use of the usual types of valves and operating means therefor, thus materially simplifying the construction and rendering its manufacture more economical, as well as eliminating sources of trouble usually found in devices of this character.

Other objects and advantages of the invention will become apparent during the course of the following description.

In the drawings I have shown one embodiment of the invention. In this showing,

Figure 1 is a side elevation,

Figure 2 is an end elevation,

Figure 3 is a central vertical longitudinal sectional view, parts being shown in elevation,

Figure 4 is a section on line 4-4 of Figure 1, and,

Figure 5 is a detail perspective view of one of the pistons.

Referring to the drawings the numeral 10 designates a cylinder block as a whole closed at its top by a head 11 secured thereto by bolts 12. Any type of cylinder block and associated elements may be employed, so far as the present invention is applicable to standard practice, and in the present instance, the cylinder block is shown as being provided with a lower flange 13 bolted as at 14 to a crank case 15 comprising upper and lower complementary portions 16 and 17. The sections of the crank case are bolted together as at 18. The crank case carries a plurality of bearings 19, the outer bearings being supported by the end walls of the crank case while the inner bearings are carried by suitable webs 20. Each bearing is provided with the usual bushing 21, and a crank shaft 22 is rotatable in these bushings in the usual manner. The crank shaft is provided with the usual cranks 23, and a fly wheel 24 is mounted upon one end of the crank shaft, as shown in Figure 3.

The cylinder block may be provided with any suitable number of cylinders as will be apparent, and in the present instance, four cylinders 25, 26, 27 and 28 are illustrated. The cylinders 25 and 27 are compression cylinders while the cylinders 26 and 28 are

firing chambers, as will be explained, a second stage of compression taking place in the latter cylinders. The cylinder head 11 is provided with a cylindrical depending projection 29 extending into each of the cylinders coaxially with respect thereto. These projections are preferably hollow to provide water spaces 30 which communicate with a water jacket 31 formed in the cylinder head. 5
 10 This water jacket also communicates with a water jacket 32 formed in the cylinder block. Pistons 33 and 34 reciprocate in the cylinders 25 and 27 respectively, while similar pistons 35 and 36 reciprocate in the firing cylinders 26 and 28. The pistons are inverted with respect to the usual types of pistons, each piston being provided with an upwardly extending skirt 37. It will be apparent that the projections 29 of the cylinder 15 heads are smaller in diameter than the cylinders thus providing an annular space into which the skirts of the piston extend upon each upward reciprocation of the latter. The compressor pistons 33 and 34 are provided in one side with ports 38, formed near the bottom of the pistons while the pistons 35 and 36 are provided with admission ports 39 spaced a material distance above the bottom of the piston for a purpose to be described. 20
 25
 30 One of the compressor pistons is shown in detail in Figure 5 of the drawings, this piston being identical with the remaining pistons except that those mounted in the firing cylinders are provided with the ports 39 previously described. Each of the pistons is provided with sealing rings 40, preferably arranged beneath the skirts 37. A wrist pin 41 is carried by each piston for connection with the upper end of a piston rod 42, the 35 lower end of each piston rod being connected to one of the cranks 23 in the usual manner. 40

Referring to Figures 3 and 4, the numerals 43 and 44 designate intake ports formed in the cylinder block and communicating respectively with the cylinders 25 and 27. The admission ports referred to are arranged in such position that they will be cleared by the pistons 33 and 34 when the latter are at their lowermost positions, the piston 33 being illustrated in such position in Figure 3. Explosive charges are supplied to the admission ports by a manifold 45 provided with an intake pipe 46 connected to a carburetor of any desired type. The contacting surfaces of 50 the manifold and the cylinder block may be machined, and the manifold is secured in position by screws 47 threaded in openings 48 formed in the cylinder block. 55

As previously stated, the firing of the 60 charges takes place in the cylinders 26 and 28, the exhaust gases passing from these cylinders respectively through exhaust ports 48 and 49. These exhaust ports communicate with an exhaust manifold 50 having an outlet pipe 51 which may be connected to the usual

muffler. The contacting surfaces of the cylinder block and the exhaust manifold also may be machined, and the manifold is secured in position by screws 52 threaded in suitable openings 53 formed in the cylinder block. It 70 will be apparent that gaskets may be employed between the cylinder block and the intake and exhaust manifolds.

Communication is adapted to be established between each compression cylinder and its associated firing cylinder through ports 54 formed in the cylinder walls between the compression and firing cylinders. This communication is established when the pistons reach the position indicated by the pistons 80 34 and 36 in Figure 3.

The explosive charges are adapted to be fired by any suitable means, and in the present instance, the head 11 is shown as being provided with threaded openings 55 in which are arranged spark plugs 56 of the usual type.

The operation of the two sets of compression and firing cylinders is the same, and only one need be referred to in detail. As the piston 33 moves downwardly, a depression 90 will be created in the cylinder 25, and as soon as the upper end of the skirt 37 of this piston clears the port 43, an explosive charge will be drawn into the cylinder 25, this charge being created by the usual carburetor and supplied to the cylinder through the manifold 45. Communication with the manifold will be cut off as soon as the piston 33 moves upwardly a relatively short distance, and further movement of this piston to the upper 100 limit of its movement compresses the charge in the cylinder 25. The full compression of the charge will be effected when the piston 33 reaches the same position as the piston 34, as illustrated in Figure 3, the downwardly projecting member 29 reducing the cubic capacity of the cylinder to effect the desired compression.

When this position of full compression is reached, the port 38 will register with the port 54 formed in the cylinder wall, 110 and the piston 35 will be in the vertical position shown in Figure 3 with the port 39 in registration with port 54, and thus the explosive charge compressed in the cylinder 25 will pass under pressure into the cylinder 26. This action will take place with the piston 35 in the vertical position shown in Figure 3, as previously stated, with the corresponding crank 180° from the position shown with the piston 35 moving upwardly. Thus the charge admitted into the cylinder 26 will be subjected to a second stage of compression upon upward movement of the piston 35, and the charge will be fired when the latter piston reaches a point adjacent its upper limit of movement, depending upon the adjustment of the ignition system.

The explosion of the charge forces the piston 35 downwardly, but the explosive charge cannot return to the cylinder 25 when the 130

piston 35 reaches the position shown in Figure 3 for the reason that the compressor piston 33 will be at the bottom of its stroke and its sleeve 37 will close the port 34. Thus the 5 expansion of the explosive charge will continue in the cylinder 26 and the piston 35 will be forced downwardly until it reaches a point adjacent its lower limit of movement, at 10 which time the upper edge of the sleeve 37 of the piston 35 will uncover the port 48 to exhaust the burned gases from the cylinder 26.

The same action takes place in the cylinders 27 and 28. During each complete reciprocation of the compressor pistons, a charge 15 of explosive mixture will be drawn into the corresponding cylinder, the charge will be compressed, and at the proper time, the charge will pass under pressure into the adjacent firing cylinder. During each complete reciprocation of either of the pistons 35 and 36, the port 54 will be uncovered to admit the explosive charge, the charge will be compressed and then fired, and finally the 25 exhaust port will be uncovered to scavenge the cylinder.

From the foregoing it will be apparent that a two-stroke cylinder engine is provided whereby an explosive charge is fired at each 30 downward movement of the pistons of the firing cylinders, and the explosive charge is subjected to two stages of compression before the firing action occurs. It also will be apparent that the admission of fresh charges 35 and the exhausting of burned charges take place at different times, thus preventing the loss of fresh charges through the exhaust ports as usually occurs with the standard types of two-cycle engines. The firing of the 40 highly compressed charges effects a more efficient chemical action as each explosion takes place, and thus the efficiency of the motor is greatly increased. The various functions of the parts referred to take place without the use of any additional elements such as valves, cam shafts, push rods, etc., and thus the motor may be economically manufactured and is so simple in construction as to minimize the danger of engine trouble 45 of various kinds.

The cranks of the two compression pistons are preferably arranged 180° apart when an engine of the type illustrated is employed, and similarly, the cranks of the firing pistons 50 also are arranged 180° apart. Thus, two explosions per revolution of the crank shaft will occur in an engine of the type illustrated, corresponding to the usual action of a four cylinder four-stroke engine. The 55 crank of each compression piston preferably is arranged substantially 90° from the crank of the corresponding firing cylinder in order to secure the most efficient results.

It is to be understood that the form of the 60 invention herewith shown and described is to

be taken as a preferred example of the same and that various changes in the shape, size and arrangement of parts may be resorted to without departing from the spirit of the invention or the scope of the subjoined claims. 70

I claim:

1. An internal combustion engine comprising a pair of cylinders having a passage affording communication therebetween, a piston reciprocable in each of said cylinders, a shaft having cranks connected to said pistons, said pistons being provided with ports adapted to simultaneously register with said passage once during each cycle of movement, and means for firing a charge in one of said cylinders, said last named cylinder being provided with an exhaust port, the other of said cylinders being provided with an intake port for the admission of explosive mixture, said pistons comprising the sole means to control 85 the movement of gases through said ports, whereby said passage is opened a substantial length of time after the opening of said exhaust port.

2. An internal combustion engine comprising a pair of cylinders having a passage affording communication therebetween, a piston reciprocable in each of said cylinders and provided with an upturned skirt portion, 90 said skirt portions being provided with ports adapted to simultaneously register with said passage once during each cycle of movement, and means for firing a charge in one of said cylinders, said last named cylinder being provided with an exhaust port, the other of said cylinders being provided with an intake port for the admission of explosive mixture, the skirt portions of said pistons comprising the sole means to control the movement of gases 95 through said ports, whereby said passage is opened a substantial length of time after the opening of said exhaust port.

3. An engine constructed in accordance with claim 2 provided with stationary means adapted to displace gases from said skirt portions as said pistons move upwardly. 110

4. An internal combustion engine comprising a firing cylinder and an explosive mixture compression cylinder having a passage adapted to afford communication therebetween, a piston reciprocable in each of said cylinders and provided with an upturned skirt portion, 115 said skirt portions being provided with ports adapted to simultaneously register with said passage when the piston of said compression cylinder is near the top of its stroke and the other piston is moving upwardly, a shaft having cranks connected to said pistons, and means for firing a charge in said firing cylinder, said compression and firing cylinders being provided with intake and exhaust ports respectively adapted to be uncovered by the skirt portions of said pistons 120 when the latter are near their lower limits of movement. 125

5. An engine constructed in accordance with claim 4 provided with stationary means adapted to displace gases from the skirt portions of said pistons as the latter move upwardly.

5 6. An engine constructed in accordance with claim 4 wherein said cylinders are closed at their upper ends by a head, and projections carried by said head and depending axially into said cylinders to displace gases from the skirt portions of said pistons as the latter move upwardly.

10 7. An internal combustion engine comprising a firing cylinder and an explosive mixture compression cylinder having a passage adapted to afford communication therebetween, a piston reciprocable in each of said cylinders and provided with an upturned skirt portion, said skirt portions being provided with ports adapted to simultaneously register with said passage when the piston in said compression cylinder is adjacent the top of its stroke, and the other piston is moving upwardly, a common shaft having cranks 15 connected to said pistons, said cranks being substantially 90° apart, and means for firing a charge in said firing cylinder, said compression and firing cylinders being provided with intake and exhaust ports respectively 20 adapted to be uncovered by the skirt portions of said pistons when the latter are near their lower limits of movement.

25 8. An internal combustion engine comprising a firing cylinder and an explosive mixture compression cylinder having a passage adapted to afford communication therebetween, a piston reciprocable in each cylinder and adapted to simultaneously uncover said passage, a shaft having cranks connected to 30 said pistons and spaced apart whereby the uncovering of said passage takes place when the piston of said compression cylinder is near the top of its stroke and the other piston is intermediate the length of its upward 35 stroke, and means for firing a charge in said firing cylinder, said compression and firing cylinders being provided with intake and exhaust ports respectively adapted to be uncovered by the skirt portions of said pistons 40 when the latter are near their lower limits of movement.

50 In testimony whereof I affix my signature.

RALPH C. MACUMBER.
